UNITED STATES PATENT OFFICE.

FREDERICK A. COLEMAN, OF GATES MILLS, OHIO.

FLEXIBLE DOOR.

1,262,643.

Specification of Letters Patent. Patented Apr. 16, 1918.

Application filed April 12, 1915. Serial No. 20,617.

To all whom it may concern:

Be it known that I, FREDERICK A. COLEMAN, a citizen of the United States, residing at Gates Mills, in the county of Cuyahoga and State of Ohio, have invented a certain new and useful Improvement in Flexible Doors, of which the following is a full, clear, and exact description, reference being had to the accompanying drawings.

10 An object of this invention is to provide a simple efficient flexible door which may be conveniently stored on a roller at one side of the opening which it closes, and which may be cheaply manufactured and easily 15 operated when in use. My door is constructed of a series of contiguous hollow metal parallel sections, and an object is so to arrange the door that when in position, a dead air space is provided within each section, thereby obtaining a very efficient heat 20 insulation. Another object is to raise and lower the door by flexible members having an engagement with successive slats and extending to the storing means. A feature of 25 my invention is the preventing of the binding in the ways guiding the door, as well as obviating the usual separate connecting means which are commonly secured to the ends of the sections and prevent ready removal and replacement of broken or injured 30 sections.

Other features of my invention will become apparent in the following specification which refers to the drawings, and the 35 essential characteristics are hereinafter set forth in the claims.

In the drawings, Figure 1 is a front elevation of my door, some of the parts being broken away for clearness of illustration; 40 Fig. 2 is a vertical cross section through the wall on which the door is carried and the casing covering the same; Fig. 3 is a vertical transverse section through the roller for receiving the door; Fig. 4 is an enlarged sectional detail of a preferred form of the sections; Fig. 5 is an enlarged sectional detail of a modified form of the sections; Fig. 6 is a sectional detail showing still another form of sections which may be used; Fig. 45 7 is a detail of the end portion of sections showing an alternate form of suspension, and Fig. 8 is an end elevation of the same.

Referring to the drawings by reference numerals, 10 indicates a wall carrying my 55 door and having an opening 12 which the door is adapted to close when in its lowered

position. The parallel sections 14 of which the door is composed, are shown as guided at their ends in channels 16 shown as secured to the wall by angle clips 17. The door may 60 be raised and lowered by flexible members 18 extending through each of the sections and shown as secured to the lower sections at 20, and to eyelets 21 in a radial shoulder of the roller 22.

65 The roller is adapted to receive the door and the radial shoulder provides for the door lying smoothly on itself as it comes to the second turn. This roller is shown as mounted on a shaft 24 carried in outwardly 70 extending brackets 25 having bearings to receive the shaft, each of the bearings being provided with a removable cap 26, to allow removal of the roller when desired.

75 One end of the shaft 24 is extended outwardly past its bearings to receive a rigidly mounted worm gear 30. This worm gear is shown as driven by a worm 32 on a shaft 33, shown as mounted in bearings 34 and 35, carried on arms extended from the brackets 80 25. On one end of the shaft 33 is a wheel 36 having pockets adapted to receive the links of a hand chain 38 extending downwardly in front of the door. It will be seen that the door may be raised and lowered by drawing on the hand chain 38, thereby rotating the worm and worm gear, which in turn drives the roller for the door. If desired, the roller may be made to rotate more rapidly by providing intermediate gearing between 90 the chain wheel and the worm. It is to be understood that this mechanism is merely 85 illustrative of any suitable mechanism for raising and lowering the door.

Although the roller may be of any suitable 95 construction, it is shown as comprising a metal sheet 40, secured to disk members 42 mounted on the shaft 24 and each having a radial shoulder as heretofore described, and shown as receiving the eyelets 21 to which 100 are attached the flexible members 18. There is preferably one of these disks 42 at each end of the door as well as at intermediate positions opposite the flexible members.

105 It is very desirable that the parallel contiguous sections of the door should articulate freely on each other and have as well a hollow interior in which air is substantially prevented from circulating, thereby affording a door which will act as a good 110 nonconductor of excessive heat, to which it would be subjected in case of fire or when

used as a closure for an oven, a furnace, or the like. In the form shown in Fig. 4, the sections comprise the parallel portions 50, above which are two inwardly extending concave portions 51, connected by an upwardly projecting convex portion 52. Below the parallel portions 50 the sides are curved inwardly and then upwardly, presenting a concave portion 54, which is complementary to the concave portion 52 of the contiguous section. When this form of section is used the lower section preferably has outwardly turned flanges 56, at the lower edges of the parallel portions 50, and adapted to rest on any suitable stop at the bottom of the door. The ends of these flanges are cut away adjacent the guideways for the door, so as not to interfere with its movement.

20 The flexible members 18 may be in the form of small cables, preferably of metal, although it is obvious that they may be chains or any other suitable connecting means. These cables are shown as extending loosely through each of the sections of the door to the lower section, to which they are secured by having an enlargement 58 at their lower ends and adapted to engage U-shaped members 59 mounted in the upper portion of the inside of the lower section and through which the ends of the cables extend.

In the form shown in Fig. 5, the sections 14 are substantially in the form of a cylindrical tube having been split longitudinally and the edges curled inwardly as at 60, thus presenting curved convex spaced portions 61, on which the convex surface of the tube above may rest, thereby closing 40 this opening and preventing the circulation of air into and out of the section.

The form shown in Fig. 6 is also that of a cylindrical tube having been split longitudinally and the adjacent edges turned outwardly as at 63, and made concave to receive the convex portion of the next section. If it is desired to secure any of the intermediate sections to the cable, a ferrule may be provided as indicated at 65, within the sections, having an intermediate portion embracing the flexible member and having outwardly turned flanges engaging the section.

In Figs. 7 and 8, is illustrated another method of supporting the hollow metal sections of my door, in which sections such as those shown in Fig. 6, for example, have inserted in their ends closures 70, preferably formed of cup-shaped sheet metal members having their closed ends 71 within the

tube. These members are split at diametrically opposite points of their projecting portions, and the edges are curled inwardly as at 73, leaving a suitable space for a chain 75. This chain is shown as having alternate flat links 76, and some of the intermediate links 77 of the chain, are adapted to embrace transverse pins 78 mounted in the projecting portions of the members 70. These chains may be secured to a suitable storing means such as a roller, in a manner similar to that heretofore described in connection with the flexible members 18. When this construction is used, there are provided in effect extensions of the sections, which close the ends of the same and through which the flexible members may extend so that any or all of the sections may be attached to these flexible members as desired.

It will be seen from the foregoing description that I have provided a door of a strong durable nature, not easily damaged and with no parts to get out of order. My door being supported at various points of its width will necessarily run evenly and smoothly in its guideway and will be prevented from sagging. A substantially dead air space is provided within each section of my door, the only open space being at the ends, which are closed either by the channel guideways or by the extensions 71.

Having thus described my invention, what I claim is:

1. In a device of the character described, the combination of a closure composed of a series of parallel contiguous hollow metal sections, closing members for the ends of said sections, flexible members extending through said closing members and attached to some of them, and guideways engaging said sections.

2. In a door of the character described, the combination of a plurality of parallel hollow sections each having a cavity on one side and a convex portion on the other side adapted to enter the cavity of the next adjacent section thereby closing the side of such section, closures for the ends of each section, each closure seating in its corresponding section, flexible members attached to said closures, and means attached to said flexible members for raising and lowering the door.

In testimony whereof, I hereunto affix my signature in the presence of two witnesses.

FREDERICK A. COLEMAN.
